UNITED STATES PATENT OFFICE.

CHARLES KATZ, OF BALTIMORE, MARYLAND.

FASTENING MEANS FOR UMBRELLA COVERS.

Application filed March 22, 1926. Serial No. 96,579.

This invention relates to umbrellas and parasols, more particularly to the fastening means for the covering thereof, and has for its object to provide, in a manner as herein-
5 after set forth, an article of such class, having its cover, formed of slicker material secured in position by a fastening means in accordance with this invention and which provides a strong, impervious and thoroughly
10 efficient covering, readily folded and extended and of materially greater lasting qualities than covers constructed from the materials now generally employed for such purposes.

A further object of the invention is to
15 provide, in a manner as hereinafter set forth, a covering for umbrellas and parasols and formed from one piece of slicker material free of connection with the umbrella ribs, other than at the tips of these latter, where-
20 by a strong, impervious, usually durable and thoroughly efficient cover is provided.

With the foregoing and other objects in view the invention consists of the novel construction, combination and arrangement of
25 parts as hereinafter more specifically described, and illustrated in the accompanying drawing, wherein is shown an embodiment of the invention, but it is to be under-
stood that changes, variations and modifications
30 can be resorted to which fall within the scope of the claims hereunto appended.

In the drawing wherein like reference characters denote corresponding parts throughout the several views:—

35 Figure 1 is an elevation of an umbrella or parasol, in accordance with this invention, and with the slicker cover extended.

Figure 2 is a fragmentary view, in inverted plan, of an umbrella or parasol in accordance with this invention, when ex-
40 tended.

Figure 3 is a fragmentary view in section of the cover.

45 Figure 4 is a fragmentary view looking toward the outer edge of the cover.

Figure 5 is a fragmentary view in section of the cover and showing the position thereof with respect to the ribs, the latter being shown in side elevation.

50 An umbrella or parasol, in accordance with this invention, can be provided with any suitable number of ribs, preferably it is constructed with ten or sixteen ribs, and is illustrated, by way of example, as formed with ten ribs. The body of the cover is formed from one piece of slicker material

having its edge reinforced throughout by an overlapping continuous binder, formed from a strip of flexible fabric, such as a length of tape. The cover is polygonal in contour
60 and the sides thereof correspond in number to the number of ribs employed.

The umbrella or parasol comprises a staff 1, a handle 2 at the inner end thereof and said handle 2 is provided with a flexible loop 3, the ordinary notched collar, not shown, which is positioned in proximity to the outer end of the staff 1 as well as being secured thereto, a head piece or ferrule 4 mounted on the outer end of the staff 1 to
70 enclose said outer end, the foldable and extendable cover supporting ribs 5 which, as is well known, are pivotally connected at their inner ends in spaced relation to the notched collar, a sleeve 7 slidably mounted on the staff 1, the foldable and extendable spreader ribs 8 which are pivotally connected to the supporting ribs 5 and to the sleeve
75 7, and a resilient latch 9 carried by the staff 1 and providing means for maintaining the
80 ribs 5 and 9 in an extended position. The foregoing elements are of known construction and it is thought unnecessary to more specifically refer to the same.

The cover comprises a polygonal shaped
85 body portion 10 and a binder 11 for the outer edge thereof. The body portion 10 is formed from one piece of slicker material, apertured at its center for the passage of the upper portion of the notched collar. The
90 edge of the central aperture snugly engages the upper portion of the notched collar and overlaps the notched portion of the collar. The manner of setting up the central portion
95 of the cover with respect to the notched collar, as stated, is well known in the art. The binder 11 overlaps the outer marginal portion of the body portion 10, as well as abuts against the outer edge thereof. The binder
100 is formed from a length of flexible tape folded to provide a pair of folds 12 and 13 and a bend 14 which abuts against the edge of the body portion 10. The binder 11 is formed from a different material from which the body portion is set up, that is to say the binder consists of a suitable fabric and the body portion is constructed of slicker material. The binder 11 is coextensive with the outer edge of the body portion
105 10 and said binder 11 is secured to said body portion 10 by a row of stitching 15 which is placed inwardly with respect to the bend 14.

In fact, the row of stitching 15 is positioned in close proximity to the inner end edge of the folds 12 and 13. The cover when in position is free of connection with the ribs 5 other than at a point in proximity to the tip of each of the ribs.

As is well known each of the supporting ribs of an umbrella or parasol, in proximity to its outer end or tip is formed with an offset portion 16 provided with an opening 17. The offset portion 16 depends from the ribs 5. The cover is secured to the offset portion 16 of the ribs 5 by flexible loops 18. Each loop 18 abuts against the end edge 15 of the bend 14 formed in the binder, see Figure 4, and is also positioned at two points against the fold 12, extends through the latter, the body portion 10, the fold 13 and through the opening 17 formed in the offset portion 16. The marginal portion of the cover is folded so that the fold 13 of the binder 11 will be positioned at each side of the offset portion and also rest upon the top of the ribs 5, see Figure 4. The bending 25 or folding of the marginal portion of the cover to position the same at each side of the ribs 5 provides a plait 19 which gradually decreases in depth from its outer toward its inner end and which has its inner end 30 terminate a substantial distance from the center of the cover. The outer edge of the

cover is positioned inwardly with respect to the tips 20 of the ribs 5.

It is thought that the many advantages of an umbrella or parasol, in accordance with this invention, provided with a cover formed from one piece of slicker material, set up in the manner as aforesaid, can be readily understood, and although the preferred embodiment of the invention is as illustrated and described, yet it is to be understood that changes in the details of construction can be had which will fall within the scope of the invention as claimed.

What I claim is:—

In an umbrella or parasol a cover formed of slicker material and having its outer portion formed with inwardly extending spaced plaits adapted to have their outer ends overlap the cover supporting ribs of the umbrella or parasol, and loop members abutting against the outer edge and outer terminal portions of the outer side faces of said plaits and further extending through the sides of the plaits for connecting the cover to the supporting ribs, each of said plaits gradually decreasing in depth inwardly and terminating at a point removed from the center of the cover.

In testimony whereof, I affix my signature hereto.

CHARLES KATZ.
